CLAIM

The ornamental design for a discharge device for a wastewater management system of a recreational vehicle, as shown and described.

DESCRIPTION

FIG. 1 is a perspective view of a discharge device for a wastewater management system of a recreational vehicle in accordance with my design.

FIG. 2 is a front view thereof.

FIG. 3 is a rear view thereof.

FIG. 4 is a left side view thereof.

FIG. 5 is a right side view thereof; and,

FIG. 6 is a top view thereof.

The broken lines shown represent portions of the discharge device for a wastewater management system of a recreational vehicle that form no part of the claimed design.

1 Claim, 4 Drawing Sheets

FIG. 1

FIG. 2**FIG. 3**

FIG. 4**FIG. 5**

FIG. 6
